Primary Examiner—Holly Baynham

(74) *Attorney, Agent, or Firm*—Michael E. McKee

(57) **CLAIM**

The ornamental design for a mounting bracket for a computer rack, as shown and described.

DESCRIPTION

FIG. 1 is a perspective view of a mounting bracket for a computer rack showing our new design;

FIG. 2 is a side elevational view thereof, as seen generally from the right in FIG. 1, and illustrating the sliding components of the bracket in one position;

FIG. 3 is a view similar to that of FIG. 2, but illustrating the sliding components of the bracket in an alternative position;

FIG. 4 is a side elevational view of the bracket, as seen generally from the left in FIG. 1;

FIG. 5 is a front elevational view thereof;

FIG. 6 is a rear elevational view thereof; and,

FIG. 7 is a top plan view thereof, the bottom plan view being a mirror image.
